UNITED STATES PATENT OFFICE

HENRY E. CURTIS, OF SAN JOSE, CALIFORNIA

ENGINE

Application filed January 3, 1929. Serial No. 330,099.

This invention relates particularly to the cooling system of an engine, and more particularly to the circulation of the water in a water-cooled internal combustion engine. It is one object of the present invention to provide a means whereby the quantity of water circulating through the cooling system of an engine may be regulated according to the amount of fuel used, the heat developed by the engine being proportioned, of course, to the fuel flow.

It is another object of the invention to provide a means of the character indicated that will be automatically adjusted to regulate the water flow by the operation of the engine.

It is still another object of the invention to provide a means of the character indicated so constructed and arranged that any desired fixed minimum amount of water may be allowed to flow through the cooling system at times when little or no fuel is being used and consequently no material amount of heat is being generated.

It is also an object of the invention to provide a device of the character indicated that will be economical to manufacture, simple in form and construction, of few parts, strong, durable, positive in action, and highly efficient in its practical application.

In the drawing:

Figure 1 is a longitudinal section through a device embodying my invention, partly in elevation and part broken away.

Figure 2 is a diagrammatical illustration showing the device operatively mounted on an engine.

Referring now more particularly to the drawing, I show at 1 a formal representation of an internal combustion engine, with a water manifold at 2, a radiator at 3, conduits 4 and 5 connecting the radiator with the engine, a water pump at 6, and a fuel intake manifold at 7 with the carburetor at 8 and throttle valve at 9.

In carrying out my invention in the manner herein disclosed, I provide an annular chamber as 10 in the conduit 4 with an annular opening 11 communicating with the manifold 2. An opening 12 is also formed in the

top of the conduit in axial alignment with opening 11.

In the side of the conduit 4 is mounted a needle-valve 13 threaded through the wall of the conduit at right angles to the axis of openings 11 and 12 and extending into the conduit as shown.

A housing is shown at 14 in the form of a cylinder having an outwardly extending flange as 15 on its lower end to fit snugly in opening 11, and an inwardly extending flange to form a seat at 16. The intermediate portion of the cylinder fits snugly in the opening 12 and an outwardly extending flange 17 seats upon the conduit 4 and is bolted thereto as at 18 thereby securing the cylinder or housing 14 in position. A number of ports 19 are formed in the wall of housing 14 in an annular row whereby communication is established between the conduit 4 and the interior of the housing. A single port as 20 is also formed in the housing 14 offset a distance from the plane of the ports 19 and in axial alignment with the adjustable needle-valve 13.

At 21 is a sleeve valve member slidably mounted in housing 14 and normally seated on seat 16, and having open communication with the manifold 2 at 22 but closed at its other end as at 23. This member is provided with ports as 24 positioned to register with the ports 19 when the member is on seat 16 as shown.

A head 25 is mounted on the outer end of the housing 14, and a spring 26 is inserted between the head 25 and the valve 21 to normally hold it on the seat 16. Inserted between the head 25 and valve 21 and encompassing the spring 26 is a bellows 27, and a conduit 28 connects the chamber formed by the bellows with the intake manifold 7 of the engine.

The result of this construction is, that normally the valve 21 is seated on the seat 16 and water flows freely from the manifold 2 into the conduit 4 and so to the radiator. But if the suction in the intake manifold 7 increases and lowers the air pressure in the bellows 27 to a point where the spring 26 can no longer maintain the valve 21 on its seat, then the

valve moves away from its seat and gradually closes the ports 19 and accordingly reduces the flow of water therethrough. If the suction becomes great enough the ports 19 will be completely closed and then the only water allowed to flow is the little that can make its way through the port 20 and the sleeve port 24 registering therewith. Ordinarily but one adjustment of the needle valve 13 is required, this adjustment being made in accordance with the type of engine used and the work it is called upon to do, although, of course it may be readily adjusted at any time if thought desirable.

An important feature of this invention is that it adjusts itself to secure the desired flow of water immediately preceding the development of the condition that requires the change of flow instead of afterwards as in the case of the thermostat, the adjustment for the water flow occurring immediately upon any adjustment of the throttle 9 and prior to any temperature change in the engine.

The movement of the valve 21 through the action of bellows 27 is limited by the stops 29 and 30.

As an example of its mode of operation, assume that the vehicle is climbing a hill with the throttle valve 9 wide open. Under this condition the sleeve valve 21 is in the position shown and the water is flowing freely through the cooling system because the suction in the bellows 27 is not sufficient to overcome the spring action, practically all of the suction generated by the engine being utilized to induct fuel into the engine through the open throttle valve 9. If, now, the vehicle passes over the top of the hill and the throttle valve 9 is closed then the opposite condition occurs. That is the suction produced by the engine is effective to operate the bellows 27 and raise the valve 21 so as to close the ports 19 and open port 20. The effect of this action is that during the descent of the hill the flow of water is so reduced that it is cooled very slowly and consequently the vehicle will arrive at the bottom of the hill with a warm engine. When the throttle is opened the fuel is inducted into an engine in proper condition to receive it and at the same time the water flow is increased in proportion to the fuel flow so that as the heating of the engine increases the water flow increases proportionately.

From the foregoing it may be clearly seen that by means of this construction the water flow is at all times and under all conditions properly proportioned to the fuel flow and is therefore always adjusted prior to the changed condition which renders the change in water flow necessary.

It is to be understood, of course, that while I have herein shown and described but one specific embodiment of the invention, changes in form, construction and method of assem-

bly and operation may be made within the scope of the appended claims.

I claim:

1. The combination with the water circulating system of an engine of a housing mounted in the system and having a port formed therein in the path of travel of the water and a second port in offset relation to the first port, and a valve member mounted in the housing and provided with a port normally registering with the first port but movable to close said first port and open the second port. 70
75

2. The combination with an engine having a fuel intake and a water circulating system, of a housing mounted in the said system having a port formed therein in the path of travel of the water and a second port formed therein in offset relation to the first port, a resiliently mounted valve member having a port formed therein normally registering with the first mentioned port, and suction actuated means connected to the intake to move the valve member against its resilient mounting to close the first mentioned port and open the second mentioned port. 80
85

3. The combination with an engine having a fuel intake and a water circulating system, of a housing mounted in the said system having a port formed therein in the path of travel of the water and a second port in offset relation to said first port, adjustable means for regulating the flow of water through the second port, a resiliently mounted valve member having a port formed therein normally registering with the first port and closing the second port, and suction actuated means connected to the intake to move the valve member against its resilient mounting to close the first port and open the second mentioned port. 90
95

4. The combination with an engine having a fuel intake and a water circulating system, of a valve mounted in the said system and provided with normally open and closed ports, and suction actuated means connected to the intake and to the valve to close the open port and then open the closed port. 100
